FLASH LAMP

Duryea E. Elmendorf, Cleveland, Ohio, assignor
to General Electric Company, a corporation of
New York

Application March 22, 1941, Serial No. 384,622

11 Claims. (Cl. 67—31)

My invention relates to flash lamps and more particularly to that type of flash lamp used for photographic purposes which comprises a bulb containing a readily combustible light-giving material which, when ignited, produces a momentary flash of actinic light of high intensity. The present application is a continuation-in-part of my co-pending application Serial No. 371,318, filed December 23, 1940.

In flash lamps in general use at present, the combustible light-producing material usually consists of a quantity of metal foil or filamentary material loosely arranged within the active portion of the bulb. To initiate the actinic reaction in such lamps, suitable ignition means is provided therefore which usually comprises a resistance element or filament embedded in a bead of ignition paste and supported within the bulb in close proximity to the loosely arranged combustible metal filling by a conventional mount structure. The ignition paste used is extremely sensitive and when the electrical circuit through the filament is energized, the heated filament promptly ignites the bead of ignition paste which, in turn, ignites the combustible material, thus initiating the actinic reaction.

Of recent date, a new type of flash lamp has been introduced in which the light-producing material consists solely of one or more beads or coatings of a readily ignitable light-producing material as the sole source of actinic light, the beads or coatings preferably being disposed on the inner leads and ignition filament of the lamp mount structure. Such a flash lamp is shown in co-pending application Serial No. 328,399—M. Pipkin, filed April 8, 1940, now Patent No. 2,291,983, dated October 4, 1942.

As a safeguard against explosion of the glass bulb when flash lamps of either of the above types are flashed, it is common practice, in the manufacture of such flash lamps, to test the completed lamp for the presence of air. One well-known method of conducting such a test, known as a coil or glow test, consists in the use of high frequency equipment, the lamp base being connected to the high potential end of the high frequency generator and the lamp bulb being placed closely adjacent an external electrode at ground potential. Such a method of testing, however, results in the loss of a considerable number of flash lamps through the premature flashing of the same, termed "flash outs," which premature flashing is caused by the occurrence of an arc discharge between the loosely arranged combustible metal filling and the ignition filament struc-

ture, or by the occurrence of a glow discharge at the portion of the leading-in wires where the bead or coating of combustible light-giving material is located. Furthermore, spontaneous flashing of such lamps is apt to occur, during handling and transportation of the same, by the development of a static charge within the combustible metal filling, the static charge building up to the point where it discharges to the filament structure, the resulting discharge igniting the lamp.

One object of my invention is to provide an improved flash lamp which will not flash prematurely when subjected to various external phenomena, such as high frequency, corona, or the like.

Another object of my invention is to provide a flash lamp which will not flash spontaneously by the development of a static charge in the loosely arranged combustible metal filling of the lamp where such a filling is used.

Still another object of my invention is to provide a flash lamp having an auxiliary or antenna wire within the bulb for the purpose of picking up or collecting the glow discharge which occurs within the lamp during the glow testing thereof.

A feature of the invention is the provision of an extension on one of the leading-in wires of the ignition filament structure, which extension projects well into the active portion of the bulb and which, in the case of flash lamps employing a loosely arranged combustible metal filling, positively contacts such filling and grounds the same to the filament structure.

Further objects and advantages of my invention will appear from the following disclosure of species thereof and from the accompanying drawing in which Fig. 1 is an elevation of one form of flash lamp comprising my invention; Fig. 2 is an elevation of another form of flash lamp according to the invention; and Fig. 3 is a diagrammatic illustration of one arrangement for testing flash lamps according to the invention for the presence of air therein.

Referring to the drawings, Fig. 1 illustrates the invention in connection with a flash lamp of the type in which the combustible light-giving material is in the form of a loosely arranged mass of metal foil, or filamentary wire or ribbon. Referring to Fig. 1, the flash lamp there shown comprises a sealed light-transmitting bulb or envelope 10 of suitable material, such as glass, having a bulbous or active portion 11 and a neck 12 provided with a reentrant stem 13. The bulb 10 is filled with a combustion supporting gaseous filling, preferably oxygen, and con-

tains a loose filling of readily combustible material 14, such as metal foil, or filamentary wire or ribbon, of aluminum or its alloys, the said metal filling being loosely arranged within the active portion 11 of the bulb. The bulb is coated on its inner or outer surface, preferably on both surfaces, with a coating of a suitable light-transmitting varnish or lacquer to thereby minimize cracking of the bulb on charge/flash and to render the bulb substantially shatter proof, as disclosed and claimed in co-pending application Serial No. 269,197—H. D. Blake, filed April 21, 1939. Mounted within the bulb 10, within effective ignition range of the combustible material 14, is a small filament 15 the ends of which are connected to leading-in wires 16, 16 which are sealed into the press portion 17 of the stem 13 and extend through the latter to the terminals of a conventional lamp base 18.

In the insertion of the filament mount into the bulb, the filament carries the metal filling 14 along with it up into the bulb. As a result, the filament is located more or less within the lower region of the mass of combustible filling material 14 so that the leading-in wires 16, 16 are normally out of effective contact with the filling material. The filament 15 and adjacent portions of the leading-in wires 16, 16 are coated with a layer of a suitable fulminating substance 19 to thereby form the primer or ignition means for the lamp. The fulminating material is preferably of the type disclosed and claimed in co-pending U. S. application Serial No. 278,288, filed June 9, 1939 by George H. Meridith and assigned to the assignee of the present application.

In accordance with the invention, one of the leading-in wires 16 is provided with a metal extension or conductor 20 which projects well into the space within the active portion of the bulb so as to extend through and contact a considerable portion of the metal filling 14 disposed therein and thereby insure positive grounding of such filling to the leading-in wires or filament mount structure. The extension or electrode 20 is preferably in the form of a wire of suitable size bent into the shape of an L and welded or otherwise secured to the leading-in wire 16 at a point intermediate the stem press 17 and the filament 15. The wire 20 is preferably secured to the leading-in wire 16 so that its longer leg 21 extends in a direction generally parallel to the axis of the bulb to a point some distance beyond or above the filament 15.

Instead of forming the grounding wire or extension 20 as a separate member suitably fastened to the leading-in wire 16, it may be formed as an integral extension of one of the leading-in wires 16, 16. Such a construction, however, does not lend itself as well to automatic manufacture of the filament mount.

Because of the positive contact of the wire extension 20 with the combustible metal filling 14, any electrical charge which is developed in the metal filling is effectively transferred therefrom through the conducting extension 20 to the leading-in wire 16. As a consequence, no discharge between the metal filling and the filament mount structure, and therefore no premature flashing of the lamp, will result.

In addition to its function as a grounding member for the metal filling 14, the wire extension 20 also serves as an additional support means therefor, the wire tending to minimize the displacement or shifting of the metal filling within the lamp bulb during transportation and

handling of the lamp and so insuring uniform characteristics of successive lamps. The wire extension 20 also seems to have the effect of speeding up the flash of the lamp by about 10 per cent or so. Such a result is definitely advantageous, since it is relatively easy to make flash lamps slower but sometimes very difficult to make them faster.

Fig. 2 illustrates the invention applied to a flash lamp of the type disclosed and claimed in the aforesaid Patent No. 2,291,983 of M. Pipkin, in which the combustible material consists solely of a bead or coating of a readily combustible light-producing substance on the inner leads and ignition filament of the lamp. I have found that when such type flash lamps are subjected to the conventional glow test which is used to detect air leakage into the bulb, a glow discharge occurs at the tips of the inner leads and instantaneously sets off the readily ignitable combustible material thereat. As a result, I have found it to be essential, in such type flash lamps, to provide an auxiliary or antenna wire within the bulb, such as shown and described in connection with Fig. 1, in order to pick up the glow discharge and so prevent accidental flashing of the lamp during the glow testing thereof. At least, no other way is known at present to those skilled in the art for preventing such accidental flashing of the lamp during the glow testing thereof.

Referring to Fig. 2, the flash lamp there shown comprises an ovoidal shaped bulb or envelope 22 having a relatively short neck portion 23 entirely enclosed and reinforced by a base 24 secured thereto. The bulb 22 is filled with a combustion-supporting gaseous filling, preferably oxygen, at a suitable pressure, for instance from 100 mm. of mercury up to one atmosphere or so, and is provided with a protective lacquer or varnish coating the same as described above in connection with Fig. 1. Sealed into the bulb 22 is a small mount structure similar to that shown in Fig. 1 comprising a reentrant stem 25 having a pair of leading-in wires 26, 26 sealed into the press portion 27 of the stem 25 and extending therethrough to the terminals of the base 24. The leading-in wires 26, 26 are provided with juxtaposed parallel inner lead portions 28, 28. Mounted substantially centrally within the bulb 22 is a small ignition filament 29 connected to the tips of the inner lead portions 28, 28. The said juxtaposed inner lead portions 28, 28 of the leading-in wires 26, 26, and the ignition filament 29, are provided with a layer or coating of a suitable fulminating light-giving substance 30 such as disclosed in the aforesaid patent No. 2,291,983 of M. Pipkin, the said substance constituting the sole source of actinic light. The light-giving substance 30 preferably consists of a mixture of magnesium and zirconium metal powders, potassium perchlorate powder and sodium chlorate powder bonded together by a suitable binder such as nitrocellulose.

In accordance with the invention, one of the leading-in wires 26 is provided with a metal or wire extension or conductor 31, similar to the conductor 20 shown in Fig. 1. As shown, the said wire 31 is secured to the leading-in wire 26 at a point intermediate the stem press 27 and the ignition filament 29 and considerably removed from the latter. The wire 31 preferably extends in the general direction of the bulb axis, in spaced relation to the inner leads 28, 28, to a point considerably beyond the ignition filament 29, and may have its upper end or tip portion 32

slightly bent toward the bulb axis so as to more or less overlie the ignition filament 29. However, the metal conductor 31 may be of any other suitable shape or form just so long as its free end or tip is spaced an appreciable distance from the ignition filament 29. Thus, the conductor 31, for instance, may consist instead of a short length of wire extending substantially straight out from the leading-in wire 16 to which it is connected, i. e., in a direction at right angles, or nearly so, to the bulb axis.

By the use of such a wire extension 31, the glow discharge which occurs within the lamp during the glow testing thereof and which would ordinarily take place at the tips of the inner leads 28, 28 where it would quickly set off the fulminating substance 30 thereat, forms instead at and about the free end or tip 33 of the wire extension 31, the said wire acting as an antenna in this respect to pick up the glow discharge. In this manner, the glow discharge is removed a sufficient distance from the fulminating substance 30 to prevent ignition of the latter.

Inasmuch as the glow discharge takes place more easily from a pointed electrode, the tip or free end 33 of the wire extension 31 is preferably pointed, such as by cutting the same at an angle, or by forming the extension 31 of fine wire so that the free end thereof approximates a point. In this way, the formation of the glow discharge at the tip 33 of the wire extension 31 is facilitated.

As in the previous modification, the antenna or electrode wire 31, instead of being formed as a separate member suitably fastened to the leading-in wire 28, may be formed as an integral extension of one of the leading-in wires 28, 28.

Fig. 3 illustrates one arrangement for testing flash lamps for the leakage of air therewith by the formation of a high frequency glow discharge therein. As shown, the apparatus comprises a downwardly inclined slip socket 34 adapted to receive the base of the lamp to be tested and contact both terminals thereof so as to short circuit the same, the said socket being electrically connected by lead 35 to one end of a Tesla coil 36. A metal cup 37, preferably of brass and filled with water, mercury or other suitable conducting liquid 38, is so arranged with respect to the slip socket 34 as to submerge in the conducting liquid 38 a small portion of the bulb 22 of the lamp to be tested when the latter is in place within the slip socket 34. The said cup 37, with its filling of conductive liquid 38, constitutes the external electrode of the testing apparatus and is connected to ground by lead 39. The end of the Tesla coil 36 opposite to that end connected to the slip socket 34 may be connected to the metal cup 37 and/or ground by lead 40 as shown, or the grounding may be taken care of by the inherent capacitance to ground of the high frequency generator 41. The low potential end of the Tesla coil 36 is inductively coupled to a source of high frequency 41 by means of an inductance 42 in the manner well-known to those skilled in the art.

The flash lamp to be tested is inserted in the slip socket 34 and properly positioned therein so that a small portion of the surface of the bulb 22, adjacent the tip thereof, is submerged within the conducting liquid 38 in the cup 37. The bulb is further positioned so that the free end or tip 33 of the metal conductor 31 is located closer to the external electrode 38 (i. e., the conducting liquid within the cup 37), than is the bead of

fulminating substance 30. This condition is always present with the arrangement shown in the drawing regardless of the rotative position of the lamp in the slip socket 34 due to the location of the tip 33 of the metal conductor 31 intermediate the bead of fulminating substance 30 and that portion of the bulb (i. e., the tip portion) which is in contact with the external electrode 38. With the flash lamp positioned in the test apparatus in the above indicated manner, the electrical circuit through the lamp is energized by the high frequency source 41, whereupon a glow discharge occurs within the lamp bulb 22 at and about the tip 33 of the metal conductor 31, the glow discharge thus being confined to a location within the bulb remote from the bead of fulminating substance 30. By observing the color of the glow discharge, the presence or absence of nitrogen within the bulb can be readily determined, a bluish-white colored glow indicating relatively pure oxygen or a good lamp while a pink or purple colored glow indicates the presence of nitrogen due to the leakage of air into the bulb.

What I claim as new and desire to secure by Letters Patent of the United States is:

1. A flash lamp comprising a sealed transparent container, a quantity of fulminating substance within said container, contact means at the exterior of said container, and a metal conductor within said container electrically connected at one end to said contact means and, in a normally operative lamp, having a free end portion extending to and terminating at a point within said container remote from said fulminating substance so that a high frequency current applied to said contact is discharged through said conductor and out of said container at a point sufficiently remote from said fulminating substance to avoid ignition of said substance.

2. A flash lamp comprising a sealed transparent container, a pair of leading-in wires extending into said container, a filament disposed within said container and electrically connected to said leading-in wires and forming therewith a continuous conductive path within said container, a quantity of fulminating material disposed adjacent to and coated on at least a portion of said filament, and a wire electrically connected to one of said leading-in wires and having a free end portion extending upwardly in the general direction of the container axis and terminating at a point above and appreciably spaced from said fulminating material.

3. The method of testing flash lamps, of the type comprising a sealed transparent bulb containing a bead of fulminating substance therein and having within said bulb a metal conductor electrically connected to an external contact of the lamp and extending to and terminating in a free end portion at a point within the bulb remote from said bead of fulminating substance, which method comprises positioning an external electrode closely adjacent the bulb of the lamp in a position nearer to the free end of the said metal conductor within the bulb than to the said bead of fulminating substance therein, and connecting said external electrode and said external lamp contact to a source of high frequency current to thereby form a high frequency discharge within said bulb at a point remote from the said bead of fulminating substance therein.

4. A flash lamp comprising a sealed transparent container, a quantity of readily combustible material within said container, means comprising

a fulminating substance and a filament disposed within said container for igniting said combustible material, said means including leading-in wires normally out of effective contact with said combustible material and arranged to carry current to said filament, and a conductive extension on one of said leading-in wires extending into effective contact with said combustible material, the said extension terminating at a point within said bulb an appreciable distance away from said fulminating substance.

5. A flash lamp comprising a sealed transparent container, a readily combustible metallic filling loosely arranged within said container, means comprising a fulminating substance disposed within said container for igniting said metallic filling, said means including leading-in wires normally out of effective contact with said metallic filling, and a conductive extension electrically connected to one of said leading-in wires and extending well into the mass of said metallic filling to thereby effectively contact and ground said filling to said leading-in wire, the said extension terminating at a point within said bulb an appreciable distance away from said fulminating substance.

6. A flash lamp comprising a sealed transparent container, a readily combustible metallic filling loosely arranged within the upper portion of said container, means comprising a fulminating substance disposed within said container at the lower region of the mass of said metallic filling for igniting the latter, said means including leading-in wires arranged within the lower portion of said container and normally out of effective contact with said metallic filling, and an upwardly extending conductor on one of said leading-in wires extending well up into the mass of said metallic filling to thereby effectively contact and ground said filling to said leading-in wire, the said conductor terminating at a point within said bulb an appreciable distance away from said fulminating substance.

7. A flash lamp comprising a sealed transparent container, a readily combustible metallic filling loosely arranged within said container, ignition means for said metallic filling comprising a filament and associated fulminating substance arranged within the lower region of the mass of said metallic filling and leading-in wires normally out of effective contact with said metallic filling, and a rigid wire extension secured to one of said leading-in wires and extending well into the said mass of metallic filling to thereby effectively contact and ground said filling to said leading-in wire, the said extension terminating at a point within said bulb an appreciable distance away from said fulminating substance.

8. A flash lamp comprising a sealed transparent container, a readily combustible metallic fill-

ing loosely arranged within said container, ignition means for said metallic filling comprising a filament and associated fulminating substance arranged within the lower region of the mass of said metallic filling and leading-in wires electrically connected to said filament and normally out of effective contact with said metallic filling, one of said wires having an integral extension projecting well into the said mass of metallic filling to thereby effectively contact and ground said filling, the said extension terminating at a point within said bulb an appreciable distance away from said fulminating substance.

9. In the manufacture of flash lamps, of the type comprising a sealed transparent bulb containing a quantity of fulminating substance, the steps which comprise providing electrode means within said bulb at a point remote from said fulminating substance and then testing for leakage of air into the bulb by applying high frequency current to the electrode means to form a glow discharge at a point within said bulb sufficiently remote from said fulminating substance to avoid ignition of said substance.

10. In a flash lamp comprising a sealed transparent container, a quantity of fulminating material in said container, electrical ignition means for igniting said fulminating material, means to carry current to said ignition means from the exterior of the container, and electrode means in said container electrically connected to a contact at the exterior of said container and terminating in a free end portion located at a point remote from said fulminating material so that a high frequency current introduced into said electrode means is carried thereby to its free end portion to form thereat a glow discharge which will indicate the presence or absence of air in the container without igniting the fulminating material.

11. In a flash lamp comprising a sealed transparent container, a pair of lead-in conductors extending into said container from the exterior thereof, a filament bridging said conductors and forming therewith a continuous conductive path within the container, a quantity of fulminating material associated with said filament so as to be ignited thereby, and electrode means comprising a conductor electrically connected to one of said lead-in conductors and terminating in a free end portion located at a point within said container remote from said fulminating material so that a high frequency current applied to said one of said lead-in conductors is carried by said electrode means to its said free end portion to form thereat a glow discharge which will indicate the presence or absence of air in the container without igniting the fulminating material.
